SEALING DEVICE

Benjamin H. Kennedy, Rochester, N. Y.

Application February 2, 1937, Serial No. 123,647

4 Claims. (Cl. 120—6)

This invention relates to devices for sealing envelopes and comprehends an improved device of this character wherein the operations of moistening the flap adhesive and folding over and pressing the flap against the body of the envelop are greatly facilitated and appreciably expedited.

Broadly the invention aims to provide in conjunction with a moistening element for the flap adhesive and a member for pressing the envelop flap in contact with the body of the envelop, guide means by virtue of which the flap is properly guided while manually moved over the moistening element and the envelop thence guided and presented to the pressure exerting means.

More specifically, the invention resides in an envelop sealing device which includes a guide member, a moistening element supported in juxtaposition thereto for moistening the envelop flap adhesive as the envelop is manually moved over the guide member, a guide member extension about which the flap is folded with relation to the body of the envelop, and a pressure member for pressing the envelop flap against the body having a flared mouth within which the guide member extension terminates.

As a further feature the invention contemplates a pressure member for pressing a moistened envelop flap against the body of the envelop to seal the same, which includes jaws resiliently urged into contact with each other and having divergent ends between which a guide member terminates.

With the above enumerated and other objects in view, reference is now made to the following specification and accompanying drawings in which there is disclosed a preferred embodiment of the invention, it being understood that variations and modifications which properly fall within the scope of the invention are covered by the appended claims.

In the drawings:

Fig. 1 is a front view of an envelop sealing device constructed in accordance with the invention.

Fig. 2 is a top plan view thereof.

Fig. 3 is a vertical transverse sectional view therethrough taken approximately on the line 3—3 of Fig. 1.

Fig. 4 is a similar view taken approximately on the line 4—4 of Fig. 1.

Fig. 5 is a similar view taken approximately on the line 5—5 of Fig. 1.

Fig. 6 is a fragmentary horizontal sectional view taken on the line 6—6 of Fig. 1.

Referring to the drawings by characters of reference, 10 designates an elongated, preferably rectangular, base upon which is mounted an upstanding longitudinally extending plate 11 adjacent one end of the base, the plate having a 5 flange 12 at its lower end which is secured by screws or equivalent fastening means 13 to said base. The plate is provided at its upper edge with a rearwardly directed horizontal flange 14, the opposite ends of which merge into rolled 10 terminal portions 15 and 16 surrounding a rod 17 which protrudes from the rolled portion 16 and terminates adjacent the opposite end of the base from that upon which the plate 11 is mounted.

A moistening element, consisting of a container 18 having a slotted upper wall 19 through which an applicator brush 20 protrudes, is mounted on the rear of the plate 11 adjacent the upper edge thereof with the brush terminals 20 protruding above the upper surface of the flange 14 whereby the flap F of an envelop E, as illustrated in Fig. 3, is guided by the flange 14 as the envelop is manually moved with reference to the plate 11. This causes the undersurface of 25 the flap F which is provided with the adhesive to be moistened and as the envelop with the moistened flap is manually moved to the right onto the protruding portion of the rod 17 and leaves the plate 11, the envelop is swung to a 30 horizontal position and the flap folded against the body of the envelop E, as shown in Fig. 4, in surrounding relation to the rod 17 which constitutes a guide member extension.

The device further includes a pressure member 35 for pressing the moistened envelop flap against the body which pressure member includes an upstanding angulated body having a rear longitudinally extending wall 21 and a transverse forwardly projecting wall 22 provided respectively 40 with horizontal lower flanges 23 and 24 secured by screws or equivalent fastening devices 25 to the base adjacent the end and forward edges thereof. The rear wall, which is slightly higher than the transverse wall 22, is provided with a 45 forwardly extending top flange 26 having an upwardly curved flange terminal 27 and constitutes a fixed pressure jaw. An arcuate resilient jaw 28 is anchored at its lower end by rivets or equivalent securing means 29 to the transverse 50 wall 22 and extends over the upper edge 30 of said transverse wall and under the fixed jaw 26 in such a manner that the jaws present towards the moistening element and guide plate 11, a flared mouth between which the extremity of the 55

guide rod 17 terminates so that the envelop with its moistened folded flap, as shown in Fig. 4, is properly presented and guided between the fixed jaw 26 and the resilient jaw 28, which jaws exert a pressure to seal the flap as the envelop is manually drawn therebetween.

In order to regulate the tension of the resilient jaw, the same is provided with a threaded stud 31 fixed thereto intermediate its ends and extending through an aperture 32 in the transverse wall 22 with a thumb nut 33 engaging the portion of the same which protrudes through the aperture 32.

What is claimed is:

- 15 1. In a device for sealing envelopes, a member for pressing the moistened gummed flap into contact with the envelop body, comprising a standard having vertical angularly related side and transverse walls, the former being of greater height than the latter and having a transverse horizontal top flange formed with an upwardly curved forward end defining an upper jaw, and an upwardly bowed resilient jaw at the upper edge of the transverse wall resiliently engaging the undersurface of the upper jaw.
- 20 2. In a device for sealing envelopes, a member for pressing the moistened gummed flap into contact with the envelop body, comprising a standard having vertical angularly related side and transverse walls, the former being of greater height than the latter and having a transverse horizontal top flange formed with an upwardly curved forward end defining an upper jaw, an arcuate resilient jaw anchored at its lower end
- 25 to the transverse wall, extending upwardly over
- 30
- 35

the upper edge thereof and resiliently engaging the undersurface of the upper jaw.

3. In a device for sealing envelopes, a member for pressing the moistened gummed flap into contact with the envelop body, comprising a standard having vertical angularly related side and transverse walls, the former being of greater height than the latter and having a transverse horizontal top flange formed with an upwardly curved forward end defining an upper jaw, an arcuate 10 resilient jaw anchored at its lower end to the transverse wall, extending upwardly over the upper edge thereof and resiliently engaging the undersurface of the upper jaw, and means for regulating the tension of the lower jaw against the upper jaw comprising a threaded stud fixed to said lower jaw, extending through an aperture in the transverse wall and a nut engaging the protruding portion of said threaded stud.

4. In a device for moistening and sealing envelopes, a base, a support mounted on said base, a longitudinally extending flange at the upper edge thereof, a rod secured to said support and projecting outwardly from one end thereof, said flange and rod providing a narrow guide over 25 which the envelopes are moved for moistening and sealing the same, a pair of jaws having oppositely curved forward portions, one of said jaws being fixed and the other having resilient engagement with the fixed jaw, and said rod having a free 30 end extending into said mouth between the jaws for guiding the envelop therebetween for sealing the same.
